CLAIM

The ornamental design for a water closet as shown and described.

DESCRIPTION

1. Water closet

FIG. 1.1 : Front

FIG. 1.2 : Back

FIG. 1.3 : Left

FIG. 1.4 : Right

FIG. 1.5 : Top

FIG. 1.6 : Bottom

FIG. 1.7 : Front perspective view

FIG. 1.8 : Back perspective view

FIG. 1.9 : Front perspective view in closed state

FIG. 1.10 : Back perspective view in closed state

FIG. 2.1 : Front

FIG. 2.2 : Back

FIG. 2.3 : Left

FIG. 2.4 : Right

FIG. 2.5 : Top

FIG. 2.6 : Bottom

FIG. 2.7 : Front perspective view

FIG. 2.8 : Back perspective view

FIG. 2.9 : Front perspective view in closed state

FIG. 2.10 : Back perspective view in closed state.

1 Claim, 20 Drawing Sheets
